WILLIAM BONSLETT, OF MCHENRY, ILLINOIS

HEAT RECLAIMER

Application filed July 29, 1932. Serial No. 626,181.

Having found that all heating plants whether steam, hot water or hot air, are low in efficiency as compared with the inherent possibilities for maximum heating effect.

5 This is due mainly to the fact that all of the hot gases and products of combustion are allowed to escape through the flue connection without delivering up their full heating values into the home. This waste is particularly true of those heaters which are equipped with oil burners and require an increased draft, the effect of which is to blow the hot gases through the flue connection before they have had an opportunity of delivering up their full heating effect.

20 Various heat economizers have been devised for utilizing this waste heat passing through the flue connection, but in general these prior constructions have been expensive in design and in installation and have not been adaptable to interchanging to the different types of heating plants.

To avoid these objections and at the same time provide a heater that is sufficient in design operation and is inexpensive to install, I have devised my present invention.

25 This invention relates to a heat reclaimer, the general object of the invention being to provide means for utilizing the products of combustion from a furnace or the like for heating fluid such as water, whereby the heat contained in the products of combustion passing to a chimney is utilized and not permitted to go to waste.

30 This invention also consists in certain other features of construction and in the combination and arrangement of the several parts to be hereinafter fully described, illustrated in the accompanying drawings and specifically pointed out in the appended claims.

35 In describing the invention in detail, reference will be had to the accompanying drawings wherein like characters denote like or corresponding parts throughout the several views, and in which:

40 Figure 1 is a side view showing the invention and its connection to a pair of chimney pipe sections leading from a side of a furnace.

45 Fig. 2 is a section on line 2—2 of Fig. 1.

Fig. 3 is a section on line 3—3 of Fig. 4, this view showing the device attached to the top of a furnace.

50 Fig. 4 is a front view of the device.

Fig. 5 is a section on line 5—5 of Fig. 3.

In these drawings, the numeral 1 indicates a casing which is provided with the end members 2 and the numeral 3 indicates a water jacket extending over the top and the sides of the casing as shown. An inlet pipe 4, which may be the return pipe of a hot water heating system is connected to the jacket space on one side of the chamber adjacent the lower end thereof and the pipe assembly 5 is connected to the opposite side of the jacket adjacent the top thereof as shown at 6 and the other end of this assembly is connected to a header pipe 7 which passes through the casing and has its opposite end closed by a cap 8. A plurality of coils 9 each 70 has one end connected with the header pipe 7 by the coupling 10 and the other ends of these coils are connected to the upper header pipe 11 by the couplings 12. This header 11 has one end closed by a cap 13 and its other 75 end suitably connected to the heating system.

55 A nipple 14 is formed in the lower part of the front end member of the casing and the nipple 15 is formed on the upper portion of the rear end member and a third nipple 16 depends from the bottom of the casing adjacent the front end thereof. An upright baffle plate 17 is connected with the bottom of the casing and extends upwardly to a 80 point a slight distance from the top thereof, this baffle plate being arranged in front of the nipple 15, and as will be seen the coils 9 are vertically arranged in the space between the front end of the casing and the baffle plate 17.

85 The nipple 14 may be connected by a pipe section 18 with the side outlet of a furnace A, as shown in Fig. 1 and the nipple 15 may be connected by a pipe section 19 with the 90 chimney. The nipple 16 is then closed by a cap 20. However, if the furnace has a smoke outlet in its top as shown at A' in Fig. 3 the cap 20 is removed from the nipple 16 and placed over the nipple 14 and a pipe section 100

21 connects the nipple 16 with the smoke outlet of the furnace A' as shown in Fig. 3.

In either case the products of combustion from the furnace enter the lower front part 5 of the casing and flow upwardly and rearwardly so that they thoroughly contact the tubes 9 after which the products of combustion pass over the upper end of the baffle 17 and escape through the nipple 15 into the 10 chimney pipe section 19. The water from the jacket enters the lower header 7 through pipe 5 and passes upwardly through the coils 9 into the upper header so that the water is thoroughly heated by the products 15 of combustion both in the coils and in the two headers before passing from the upper header.

By projecting both ends of the headers from the ends of the casing and providing 20 the caps 8 and 13, the headers can be connected to the system in different ways, or may be connected to two radiators at same time.

Thus I have provided a simple device for 25 utilizing the products of combustion which usually go to waste up the chimney, for heating the water or other fluid which may be used in the regular heating system or in an auxiliary system.

30 As will be seen the return water is first heated in the water jacket which, of course, is heated from the sides and top of the casing and then the water from the jacket enters the lower header 7 thru the pipe assembly 5 35 and then passes through the coils into the upper header. Thus practically all the heat of those products of combustion passing to the chimney is utilized in heating the water.

It is thought from the foregoing description 40 that the advantages and novel features of the invention will be readily apparent.

It is to be understood that changes may be made in the construction and in the combination and arrangement of the several parts 45 provided that such changes fall within the scope of the appended claims.

Having thus described my invention, what I claim as new is:—

1. A heat reclaimer comprising a casing, 50 means for connecting the front portion thereof to the furnace section of a chimney pipe, means for connecting the rear portion to the chimney section of said pipe whereby the products of combustion from the furnace will 55 pass through said casing, a baffle in the rear part of the casing and extending upwardly from the bottom thereof, header pipes passing through the casing, coils vertically arranged and having their ends connected with 60 the header pipes, a jacket surrounding the casing, a supply pipe connected to one side of the jacket adjacent the bottom thereof, a pipe connected with the opposite side of the jacket adjacent the top thereof, means for 65 connecting the last-mentioned pipe to the in-

let header and an outlet pipe connected with the outlet header.

2. A heat reclaimer for use on a chimney pipe comprising a casing having its front end connected to the furnace section of said chimney pipe and its rear end to the chimney section of said pipe, coils located in the casing, said coils being contacted by the products of combustion passing through the casing, a jacket surrounding the sides and top wall of the casing, a supply pipe connected to the lower part of one side of the jacket, and means for connecting the other side adjacent the top thereof with the inlet ends of the coils, and outlet means connected with the outlet ends of the coils. 70 75 80

3. A heat reclaimer of the class described comprising a casing having an inlet nipple at the lower part of its front end, and an outlet nipple adjacent the upper end of its rear end, and a third nipple depending from the bottom of the casing adjacent the front end whereby the outlet nipple can be connected to a chimney and either the front nipple or the bottom nipple to a furnace outlet, a cap for closing that nipple not in use, a coil in the casing, inlet and outlet headers connected with the coils, said coils being located in the path of the products of combustion passing through the casing, and an upright baffle connected with the bottom of the casing and spaced from the top thereof, and arranged in spaced relation in front of the outlet nipple. 85 90 95

4. A heat reclaimer of the class described comprising a casing having an inlet nipple at the lower part of its front end, and an outlet nipple adjacent the upper end of its rear end, and a third nipple depending from the bottom of the casing adjacent the front end whereby the outlet nipple can be connected to a chimney and either the front nipple or the bottom nipple to a furnace outlet, a cap for closing that nipple not in use, coils in the casing, inlet and outlet headers connected with the coils, said coils being located in the path of the products of combustion passing through the casing, an upright baffle connected with the bottom of the casing and spaced from the top thereof, and arranged in spaced relation in front of the outlet nipple. 100 105 110

Having thus described my invention, what I claim as new is:—

WILLIAM BONSLLETT.
